TYPEWRITER, CALCULATING MACHINE,
AND THE LIKE

Joseph Patrick O'Halloran and Alan Edward Crocker, London, England, assignors to Okopa Carbon Paper Eliminator Limited, London, England

Application March 24, 1939, Serial No. 263,989
In Great Britain March 26, 1938

2 Claims. (Cl. 197—153)

In Patent No. 2,148,217 (Serial No. 132,867) is described an attachment for typewriters, calculating machines and the like in which an auxiliary ink ribbon is employed in addition to the main ink ribbon for the purpose of making an original and one or more copies without the use of carbon paper, the auxiliary ribbon being carried on a pair of spools, one mounted on the carriage and the other on the body portion of the typewriter, the carriage-carried spool being actuated on operation of the line space lever to wind ribbon thereon from the other spool against the action of a spring associated with said other spool.

An object of the invention is to provide improved means for avoiding overstraining of the spring in an attachment of this character.

A further object of the invention is to enable a relatively short spring to be used to control the feed of a long length of ribbon.

Another object of the invention is to prevent damage of the spring due to improper fitting of the spools.

With these and other objects in view, the invention consists in the features of construction, hereinafter more particularly described, which are claimed in the appended claims.

One embodiment of the invention will now be described in detail, by way of example, with reference to the accompanying drawings, in which:

Figure 1 is a perspective view of a conventional typewriter fitted with an auxiliary ribbon feed mechanism constructed in accordance with the invention;

Figure 2 is a section through the platen of the typewriter, showing how the paper sheets are fed into the proper position relatively to the main and auxiliary ribbons;

Figure 3 is a perspective view of the separating pan;

Figure 4 is a sectional view through the mechanism associated with the right hand spool;

Figure 5 is a plan view of this mechanism with the cover removed;

Figure 6 is a bottom plan view of the mechanism shown in Figure 4;

Figure 7 is a top plan view, with the cover removed, of the mechanism for actuating the left hand spool, and

Figure 8 is a section along the line VIII—VIII in Figure 7.

Like reference numerals indicate like parts throughout the drawings.

The typewriter may be of any standard type and comprises a fixed body portion 10 on which

is supported the usual travelling carriage 11 carrying the platen 12. The machine includes the usual typewriter keys 13, type bars 14, spools 15 for the main ribbon 16 and ribbon vibrator 17. One of the spools 15 is driven by a pawl and ratchet mechanism (not shown) in known manner to present a fresh portion of the main ribbon at the printing position after the typing of each character.

In order to equip the machine with an auxiliary ribbon and thereby dispense with the use of carbon paper, it is fitted with two additional spools 18, 19 for the auxiliary ribbon 20 which are attached respectively to the carriage and to the body of the machine, with guides 22 for the auxiliary ribbon and with a paper-separating pan 24. The guides 22 are fixed by screws to the carriage. The spool 18 is supported by a bracket 26 secured to the carriage, and the spool 19 is supported by a bracket 27 attached to the body portion of the machine. The top bar 29 of the pan 24 is attached to the carriage by screws and carries four projecting shield members 31 which extend around the platen 12 inside the paper guide 32 (see Figure 2) and serve to feed the sheets of paper to the correct position. The forward end of each shield member 31 is thinned to a fine edge at 33, these edges being located just behind the lower edge of the auxiliary ribbon 20 when the parts are assembled.

In order to make two copies, three sheets of paper *a*, *b*, *c* are inserted into the machine at the top, as indicated by Figure 2, and caused to travel round to the printing line by turning the platen by means of the knob 34. As will be seen, the pan 24 diverts the front two sheets into position between the two ribbons, while the rear sheet *a* is brought into position behind the auxiliary ribbon 20. An original imprint of the matter typed will then be made on the front surfaces of the sheets *a*, *c* and on the rear surface of the sheet *b* which should be of thin paper so that the matter typed on it can be read from the front. If extra copies are required these may be made with carbon paper between the sheet *a* and the platen in the ordinary way. The transparent sheet *b* could be omitted if desired, but in this case it is desirable to introduce a shield of Celuloid or other convenient material behind the sheet *c* to prevent its rear surface from receiving an imprint from the auxiliary ribbon.

The auxiliary ribbon is kept under a tension sufficient to prevent it from sagging and soiling the paper by means of a spiral spring 35 associated with the spool 19, no guide extending along 55

the printing line being necessary. The spring 35 is located in a box 21 fixed to the bracket 27 and having a cover 36. The outer end of the spring is fixed by means of a screw 23 to the box 21 and its inner end is turned over to engage a slot in a sleeve 28 which is rotatably mounted on at shaft 37.

The left hand spool 18 is carried on a spindle 71 which is rotated clockwise, as seen from above, 10 on each actuation of the line space lever 38. This is effected by mechanism located in a box 39 having a cover 40, the box being attached to the bracket 26. On the spindle 71 is fixed a ratchet 41 which is driven at each actuation of the line

15 space lever by a pawl 42 pivoted at 43 to a rocking lever 44, and held in contact with the ratchet by a spring 45. The rocking lever 44 is pivotally mounted on the spindle 71 and connected to the line space lever by a linkage consisting of links

20 46, 47, spindle 51 and links 52, 48. On actuation of the line space lever, the lever 44 is rocked clockwise, as seen from above, thereby rotating the ratchet 41 which is held by means of a check pawl 49 in the position to which it has been ad-

25 vanced by the pawl 42. On release of the line space lever, a spring 50 returns the rocking lever 44 to its original position, the ratchet 41 sliding over the teeth of the pawl 42 during this movement. The spool 18 carries a downwardly pro-

30 jecting pin 78 which is engaged by a laterally projecting pin 72 carried on the spindle 71 so that the spool will be caused to turn with the spindle. A spiral spring 70, the purpose of which is explained below, is disposed between the pin 12 35 and the lower surface of the spool, and the spool is held in position with its pin 78 in the path of the pin 72 by means of a screw cap 69.

At each actuation of the line space lever, therefore, a portion of the auxiliary ribbon will be 40 drawn over to the spool 18 from the spool 19. The spool 19 is mounted on a spindle 53 carrying at its lower end a pinion 54. The spool 19 carries a downwardly projecting pin 79 which engages with a pin 76 projecting laterally from the spindle 53, so that the spindle will be caused to turn with the spool. The spool is held in position by means of a screw cap 77.

The pinion 54 meshes with a gear wheel 55 which is rotatably mounted on a spindle 56. 50 Fixed to the spindle 56 is a ratchet 57, with which co-operates a pawl 58 pivotally mounted on the gear wheel 55 and held in co-operation with the ratchet by means of a spring 59. The unwinding of the ribbon from the spool 19 causes the spindle 53 to be turned in an anti-clockwise direction, as seen from above, with the result that the gear wheel 55 is turned clockwise and consequently the ratchet 57 and spindle 56 are likewise turned clockwise. On the spindle 56 is fixed a pinion 60 meshing with a gear wheel 61 fixed to the top 55 of the sleeve 28, to which is connected the inner end of the spring 35. The action of unwinding the ribbon, therefore, causes the spring to become wound up. A pin 62 connects the gear wheel 61 with a flange 63 on the upper end of the shaft 37, so that this shaft will rotate with the sleeve 28. At the bottom of the shaft 37 is a safety device, shown in Figure 6, for preventing the spring from being overstressed.

70 This safety device consists of a Geneva stop mechanism comprising a member 64 fixed to the lower end of the shaft 37 and having a single tooth 65 co-operating with the Geneva stop member 66, which is rotatably mounted on a pin 67. 75 For each revolution of the shaft 37, the stop mem-

ber 66 is rotated by one tooth, it being held against further movement by contact of the periphery of the member 64 with the periphery of one of its own teeth. When the shaft 37 has turned through four revolutions, the large tooth 68 will come into co-operation with the tooth 65, as shown in Figure 6, and will lock the shaft 37 against further rotation, and thus prevent overstressing of the spring 35.

It will be appreciated that, owing to the inter- 10 position of the gearing between the sleeve 28 and the spindle 53, the spring 35 can be of quite short length and yet control a very long length of ribbon.

Normally the whole of the ribbon will be un- 15 wound from the spool 19 before the locking device, shown in Figure 6, comes into operation and this locking device is provided so as to act as a safeguard in case an extremely long ribbon were to be employed. When it is desired to return the 20 ribbon to the spool 19, the cap 69 on the spindle 71 is unscrewed, when the spring 70 automatically uncouples the spool 18 from the spindle 71, whereupon the spring 35 will be free to turn the spindle 53 in clockwise direction, as seen from 25 above, and rewind the ribbon. The spring 70 acts as a brake to prevent the rewinding from proceeding too rapidly and the rewinding action stops when the stop member 66 has rotated clockwise from the position shown in Fig. 6, into the 30 position in which its large tooth 68 lies immediately above the tooth 65. This sets a limit to the unwinding of the spring, which is given an initial tension so that, even when it has unwound as far as it is allowed to by the locking device, it 35 tensions the ribbon. The ribbon is thus prevented from vibrating or becoming slack throughout the whole of the rewinding operation. This initial tension in the spring will moreover ensure that the ribbon will be kept taut so as not to 40 smudge the papers during the early portion of the feeding from the right to the left hand spool.

The pawl and ratchet connection between the gear wheel 55 and the spindle 56 acts as a safeguard against damage of the spring in case the 45 spool 19 should inadvertently be placed on the spindle 53 the wrong way up. In this case the pawl 58 will simply click over the teeth of the ratchet 57 and the spindle 56 will not be turned. The clicking noise will warn the operator that 50 the spool is wrongly fitted.

It will be appreciated that the invention is applicable not only to typewriters, but also to calculating and like machines in which printing is effected by means of typebars, and the expression "typewriting machine" in the appended 55 claims is to be read as including calculating machines and the like.

What we claim as our invention and desire to 60 secure by Letters Patent:

1. A typewriting machine, comprising in combination a fixed body portion, main ribbon spool-receiving spindles on the said body portion, auxiliary spool-receiving spindles, driving means for effecting intermittent rotation of one of the said 65 auxiliary spindles to wind an auxiliary ribbon on to the spool carried thereon, a spring coiled in a flat spiral associated with the other auxiliary spindle for holding the auxiliary ribbon in tension, reduction gearing between said driven auxiliary spindle and the spiral spring, ratchet and pawl mechanism associated with said reduction gearing to prevent rotation of the driven auxiliary spindle in a direction to unwind the spiral spring, a device to prevent excessive rotation of 70 75 75

the driven auxiliary spindle in either direction, and means for releasably coupling the ribbon spool to the driving spindle to permit on release uninterrupted reverse feed of the auxiliary ribbon by the spiral spring.

5. A typewriting machine, comprising in combination a fixed body portion, a paper carriage slideable in the body portion, main spindles on the body portion for receiving the main ribbon spools, auxiliary spindles for receiving auxiliary ribbon spools, one of said auxiliary spindles being mounted on the carriage while the other is mounted on the body portion, line space mechanism, driving means associated with the line space mechanism for intermittently rotating the carriage-carried auxiliary spindle to wind the auxiliary ribbon on to the spool carried thereon,

10 a spring coiled in a flat spiral associated with the other auxiliary spindle for holding the auxiliary ribbon in tension, reduction gearing between said driven auxiliary spindle and the spiral spring, ratchet and pawl mechanism associated with the 5 said reduction gearing to prevent rotation of the driven auxiliary spindle in a direction to unwind the spiral spring, a device to prevent excessive rotation of the driven auxiliary spindle in either direction and means for releasably coupling the 10 ribbon spool to the driven auxiliary spindle to permit, on release of said coupling, uninterrupted reverse feed of the auxiliary ribbon by the spiral spring.

JOSEPH PATRICK O'HALLORAN. 15
